CONTAINER

William J. Wardell, Mount Vernon, N. Y., assignor to American Can Company, New York, N. Y., a corporation of New Jersey

Application October 4, 1934, Serial No. 746,863

6 Claims. (Cl. 221—62)

The present invention relates to dredging cans and has particular reference to a fully sealed can which is opened by breaking out of scored parts, such a can being provided with a sliding member of simple construction and one which is retained in a unique manner on the end of the can so that it functions selectively to close the can after it has been opened or to expose certain of its openings for dispensing purposes.

5 An object of the invention is the provision of a sealed dredging can which is provided with a sliding member retained in sliding condition within the seat or panel of an imperforate can end that is perforated to open the can, the retaining means being flattened beads struck out as integral parts of the can end wall which hold the slide against displacement and at the same time allow for its free manipulation to cover and uncover the perforations.

10 Another object of the invention is the provision of a sealed rectangular dredging can having a sliding member which is movable back and forward to cover and uncover pouring and sifter openings which are made in a wall of the can when it is opened, the can wall being provided 25 with opposed beads for guiding the slide in its movement, flattened sections of the beads being used to retain the slide in operative condition.

15 Another object of the invention is the provision of a dredging can of the character described wherein the sliding member is provided with locating means for accurately positioning it for closing of both pouring and sifting openings or for selectively uncovering either of them.

20 A further object of the invention is the provision of a round sealed dredging can having an imperforate end formed with a circular sunken panel or seat outlined by a peripheral bead or rim for the reception of a rotatable slide member, 25 the latter being retained against displacement by flattened sections of the circular bead which overhang the peripheral edge of the slide, the position of the slide member within its seat determining the type of dispensing action for the can contents, after opening of the can by perforating its end, or effecting a closure for all of the openings in the can end wall.

25 Numerous other objects and advantages of the invention will be apparent as it is better understood from the following description, which, taken in connection with the accompanying drawing, discloses a preferred embodiment thereof.

Referring to the drawing:

30 Figure 1 is a perspective view of a rectangular

dredging can embodying the present invention;

Fig. 2 is a top plan view of the same;

Fig. 3 is a plan view of a round can embodying the present invention;

5 Figs. 4 and 5 are longitudinal sectional views taken substantially along the line 4—4 in Fig. 2, Fig. 4 illustrating the can prior to its opening and Fig. 5 showing the same after opening; and

10 Figs. 6 and 7 are transverse sectional views taken respectively along the lines 6—6 and 7—7 in Fig. 2.

The present invention is concerned with a dredging can having a sliding closure member and Figs. 1, 2, 4 to 7 inclusive illustrate the invention as it is applied to a rectangular can while 15 Fig. 3 illustrates the application to a round can.

Considering first the rectangular form of can the drawing illustrates a rectangular body 11 preferably formed of metal provided with an imperforate bottom or end member 12 and an 20 imperforate metal top end member 13. The member 13 may be secured to the upper end of the body 11 in the usual double seam 14.

The top end 13 of the can is of the usual sunken panel or dished form required for double seam- 25 ing with a surrounding panel wall 15 which is at right angles to a web wall 16. A second sunken panel 17 is formed in the end panel wall 16 and its outer edges are substantially parallel to the boundary wall 15. On two opposite sides of this 30 panel within a panel, the web wall 16 is beaded as at 18 (Figs. 2 and 7) to provide a pair of opposed beaded rims.

The bottom part of the panel 17 is flat and this section (designated by the numeral 21) is 35 partially cut through in score lines 22. The metal within the score lines is adapted to be pushed down and inside of the can as an incident to opening the can and a pouring opening 23 and sifter openings 24 are thereupon formed as best 40 illustrated in Fig. 5.

A metal slide member 31 is provided for sliding engagement with the flat panel wall 21 and is located within the panel 17. It has its opposite 45 edges in sliding engagement between the upstanding bead rims 18 formed in the can end wall. At intervals the bead rims are flattened to provide retaining lugs 32 which extend in and overhang the longitudinal edges of the slide member. These retaining lugs hold the slide member 50 against displacement from its panel seat and at the same time allow for a free although restricted longitudinal movement.

The two ends of the slide member 31 are curled 55 to provide finger pieces 35 and these permit easy

manipulation of the slide back and forth within its panel seat. Prior to opening of the can the slide has no utility, as the imperforate top before perforation acts in its capacity to seal the 5 contents. After the openings 23, 24 are formed the slide functions in accordance with its position within its panel seat.

When the slide member 31 is in its central position both the pouring opening 23 and the 10 sifter openings 24 are covered and in this position the slide acts as a closure for the can. When the slide member is moved toward the right (Figs. 1, 2 and 5) the sifter openings 24 are uncovered and a sifting of the contents may be had through 15 the sifter openings. When the slide member is in the opposite end of its seat, the sifter openings 24 are covered but the pouring opening 23 is uncovered. The can contents may then be dispensed through the latter.

20 The flat slide 31 may be reinforced by an oblong bead 36 which is struck up from the metal and a central button 37 is also preferably pressed in the metal of the slide just inside of the oblong bead. This bead 36 in addition to strengthening 25 the slide is utilized, as is also the button 37, in a locating stop capacity as will now be further explained.

The flat wall 21 of the recessed can top is pressed up at its center into a button 38, best 30 illustrated in Fig. 4. This button cooperates selectively with the two ends of the oblong bead 36 or with the button 37 in locating the slide in one of its three positions. The button 37 of the slide engages with the can end button 38 when 35 the slide is in its central or can closing position. In the other two positions of the slide, the button 38 snaps into one or the other ends of the bead 36 and in like manner definitely locates the slide in its pouring or sifting positions.

40 In the adaptation of the instant invention to a round can, the circular end (designated by the numeral 41, Fig. 3) is formed with a circular depression or panel 42 which in this form is preferably surrounded with a circular bead rim 43. A rotatable slide member 44 is herein provided and is located inside of the surrounding bead rim 43. This beaded rim is flattened at spaced intervals as at 45 to provide retaining lugs which overhang the periphery of the rotatable slide 50 44 and keep it in its seat while permitting free rotation.

The wall of the end inside of the sunken panel 42 is partially cut through in an oblong or kidney shaped score line 46 and in several circular score 55 lines 47. The scores are broken through and the metal of the end inside of the score lines is pushed into the can in the same manner as before when the can is opened. This displacing of the metal provides a pouring opening 48 and sifter openings 60 49.

The rotatable slide 44 is also formed with a kidney shaped opening 51 and when this is brought into register with the pouring opening 48 the can 65 contents may be dispensed therethrough. In like manner a registration with the sifter openings 49 permits sifting of the can contents. When the slide opening 51 is out of register with either the pouring or the sifter openings the slide functions as a closure for the opened can. A finger piece 52 struck up from the slide wall or attached thereto provides for easy manipulation of the slide to rotate it into its several positions.

70 It is thought that the invention and many of its attendant advantages will be understood from 75 the foregoing description, and it will be apparent

that various changes may be made in the form, construction and arrangement of the parts without departing from the spirit and scope of the invention or sacrificing all of its material advantages, the form hereinbefore described being 5 merely a preferred embodiment thereof.

I claim:

1. A dredge top can, comprising an imperforate metal end member having a sunken panel and an upstanding beaded rim adjacent the edge 10 of the panel, pouring and sifter openings outlined by score lines cut in said panel wall, the metal within the score lines being adapted to be pressed inside of the container to open the same, a slide member located inside of said sunken panel 15 and having a thickness substantially equal to the depth of the latter, said slide member having an edge adjacent said beaded rim, the latter being flattened at spaced intervals to provide retaining lugs which project over said slide edge 20 and slidably retain the slide in its seat so that it is movable into different positions to cover both pouring and sifter openings or to selectively cover only one of said openings.

2. A dredge top can, comprising an imperforate metal end member having a sunken panel with a flat wall and an upstanding beaded rim adjacent the edge of the panel, pouring and sifter openings outlined by score lines cut in the flat wall of said panel, the metal within the score 30 lines being adapted to be pressed inside of the container to open the same, and a flat slide member located inside of said sunken panel and having its top surface substantially in the plane of said metal end member, said slide member being 35 engageable with the flat wall thereof and having an edge adjacent said beaded rim, the latter being flattened at spaced intervals to provide retaining lugs which project over said slide edge and slidably retain the slide within its seat, and 40 a finger piece associated with said slide member for moving it within its seat to close the container after it has been opened or to selectively open said pouring or said sifter openings.

3. A dredge top can, comprising an imperforate metal end member having a sunken panel and an upstanding continuous beaded rim adjacent the edge of the panel, pouring and sifter openings outlined by score lines cut in said panel, the metal within the score lines being adapted to be pressed inside of the container to open the same, a slide member located within said sunken panel and having an opening, the top surface of said slide member lying substantially in the plane of said metal end member, the edge of 55 said slide being adjacent said beaded rim and the latter being flattened at spaced intervals to provide retaining lugs which project over the edge of said slide and slidably retain it in its seat so that it is movable to carry its opening out of register with both pouring and sifter openings or to selectively register with one or the other of said openings.

4. A rectangular dredge top can, comprising an imperforate metal end member having a 65 sunken panel and a pair of spaced beaded rims formed in said panel and on opposed edges thereof, pouring and sifter openings outlined by score lines cut in said panel, the metal within the score lines being adapted to be pressed inside 70 of the container to open the same, and a rectangular slide member located inside of said sunken panel and slidably longitudinally thereof with its longitudinal edges in engagement with said spaced rims, said rims being flattened at 75

spaced intervals to provide retaining lugs which project over the edges of said slide and prevent the displacement of the slide member while permitting covering or uncovering of said pouring or sifter openings.

5. A rectangular dredge top can, comprising an imperforate metal end member having a sunken panel and a pair of spaced beaded rims formed in said panel and on opposed edges thereof, pouring and sifter openings outlined by score lines cut in said panel, the metal within the score lines being adapted to be pressed inside of the container to open the same, and a rectangular slide member located inside of said sunken 10 panel and slidable longitudinally thereof with its longitudinal edges in engagement with said spaced rims, the latter being flattened at spaced intervals to provide retaining lugs which project over the edges of said slide and prevent its displacement, and locating elements formed in said 15 can end and in said slide for positively locating

the slide in different longitudinal positions to cover or uncover either said pouring or said sifter openings.

6. A round dredge top can, comprising an imperforate metal end member having a sunken 5 panel and an upstanding circular beaded rim formed adjacent to and surrounding said panel, pouring and sifter openings outlined by score lines cut in said panel, the metal within the score lines being adapted to be pressed inside of the container to open the same, and a rotatable slide member located inside of said sunken panel and having a thickness substantially equal to the depth of the latter, the periphery of said slide member being surrounded by said circular beaded 10 rim, said rim being flattened at circumferentially spaced points to provide retaining lugs which project over the peripheral edge of said rotatable slide member to hold it in position for opening or closing said pouring and sifter openings. 15 20

WILLIAM J. WARDELL.
